2,457,483

STRETCH-FORMING APPARATUS, INCLUDING A SEGMENTAL DIE CONNECTED AT OPPOSITE ENDS TO SHIFTABLE VISES

Royal E. Martin, Mansfield, Ohio

Application October 2, 1946, Serial No. 700,654

5 Claims. (Cl. 153—48)

1

This invention relates to stretch-forming apparatus, and particularly relates to apparatus for stretch-forming aluminum or other metal shapes or extruded sections, such as angles, tees, channels, hat channels, etc.

Stretching materials of the class described beyond the elastic limits thereof while being formed has well-known advantages, in that materials formed in this manner will hold given accurate shapes without substantial spring-back. The methods utilized in the past for stretch-forming such materials, however, have been generally unsatisfactory for various reasons. One method, for example, utilize a pair of relatively fixed vises for gripping opposite ends of a part while a separate die of fixed contour was moved away from the vises to form the part, but this procedure was not entirely satisfactory because of the great difficulty of changing the shape or contour of the die to obtain accurately formed parts, and was also objectionable particularly because of frequent breaking or rupturing of the material due to excessive stretching thereof in the area between the gripping vises and the die. Other well-known methods of forming have utilized various arrangements of driven rollers or rotary dies, but these methods have been extremely objectionable because they involved the use of uneconomical "cut and try" forming operations requiring frequent checks by application of the part to a contour or other template. In many instances these rolling methods could not be satisfactorily used for forming parts of certain cross-section, as for example hat channels. Other methods have similarly been unsatisfactory in various respects.

A general object of this invention is to provide stretch-forming apparatus of the character described, which is operable to form the material accurately to desired shape or contour, without the use of so-called "cut-and-try" methods in forming on a production basis, and in use of which is obviated rupturing or breaking of the material due to excessive stretching applied at localized areas.

Another object of the invention is to provide apparatus of the character described which may be readily altered, either to adjust the shape or contour of the parts being produced without necessarily changing the contour or shape of the forming portions of the die, or to interchange the forming die parts for producing an entirely different part.

Another object of the invention is to provide apparatus of the character described wherein

the parts to be formed are substantially uniformly stretched throughout the entire lengths thereof.

Another object of the invention is to provide apparatus of the character described including a flexible segmental die, and having improved means for regulating the relative angular velocities of the segments with respect to each other in proportion to the requisite forming functions thereof.

Another object of the invention is to provide apparatus of the character described including a sectional forming die, having improved take-up means for assuring uniform initial strain on the part when the die is flexed for the forming operation.

Another object of the invention is to provide apparatus for stretch-forming parts of the character described which does not require any substantial degree of skill to operate or adjust.

These and other objects of the invention will be manifest from the following brief description and the accompanying drawings.

Of the accompanying drawings:

Figure 1 is a top plan view illustrating stretch-forming apparatus embodying the features of the invention, the same being shown in inoperative position.

Figure 2 is a front elevational view thereof.

Figure 3 is a top plan view of the apparatus shown in Figure 1, but in operative position.

Figure 4 is an enlarged fragmentary cross-section taken substantially on the line 4—4 of Figure 1.

Figure 5 is an enlarged fragmentary detail view, as viewed from the front of the apparatus, illustrating improved take-up means for the die segments.

Figure 6 is a fragmentary detail view, partly broken away and in section, taken substantially on the line 6—6 of Figure 2, and particularly illustrating one of the vises.

Figure 7 is a cross-section taken substantially on the line 7—7 of Figure 6.

Figure 8 is a top plan view of a modified form of the invention.

Referring particularly to Figures 1, 2 and 3, the numerals 10 and 11 designate a pair of vises mounted in spaced relation on a flat support or table top 12, for restrainingly gripping opposite ends of a part P to be formed arcuately in a manner to be described later. The left hand vise 10 is pivoted at 13 to a bracket 14 secured to the support 12, to be swingable rearwardly of the support as viewed in Figures 1 and 3. The right hand vise 11 is provided with a U-shaped guide or

retaining member 14, through which is received a roller 16 mounted on a bracket 17 secured to the top of support 12, whereby the vise 11 is swingable rearwardly about the center of the roller 16, but the guide member 15 being proportioned to permit lateral relative shifting movement of the vise with respect to the roller 16.

The detail construction of the vise 11 is best illustrated in Figures 5, 6 and 7, the same comprising a hollow cylindrical casing 18, at the inner end of which is provided oppositely disposed tapered seats or guide portions 19 and 20 for slidably receiving a pair of oppositely disposed guide blocks 21 and 22. The inner faces of these blocks are shaped correspondingly to the cross-section of the part P to receive the ends thereof therebetween, when the blocks are moved together by inward sliding movement thereof along the guide portions 19 and 20 (see Figures 7 and 8). For slidably retaining the blocks 21 and 22 against the guide surfaces 19 and 20, they may be provided with apertures 23 and 24, in parallelism to the corresponding guide surfaces, in which are slidably received guide pins 25 and 26 fixedly secured at 27 and 28 to the interior of casing 18. To accomplish axial shifting the blocks 21 and 22 toward and from clamping engagement thereof with the ends of part P, outwardly axially extending pins 29 and 30 on the outer ends of the blocks 21 and 22 may have spaced retaining portions at their free ends for engaging opposite sides of a plate 31, which is radially slotted at 32 and 33 for receiving the ends of said pins. Secured to the plate 31 is a rod 34 which extends through a central guide aperture 35 in a removable cap 36 on the outer end of casing 18. The outwardly projecting end of rod 34 is pivoted at 37 to a handle 38, an extension 39 of which is pivoted at 40 to a lug 42 extending outwardly of cap 36. The arrangement is such that the handle 38 is movable as shown between the full and chain-dotted lines of Figure 7, to move the blocks 21 and 22 in either direction axially of the casing 18. This axial movement of the block, as guided by the pins 25 and 26 and the guide surfaces 19 and 20, causes radial movement of the blocks, with which movement the parts 29 and 30 slide in the slots 32 and 33 of plate 31. The handle 38 is movable from the chain-dotted line to the full-line positions thereof shown in Figure 7, to move the blocks 21 and 22 radially inwardly of each other and thereby to apply requisite clamping or gripping action to the ends of part P. The clamping mechanism of vise 10 may be substantially the same as that of the vise 11.

Mounted between the vises 10 and 11 may be an elongate flexible forming die 43, which comprises three connected segments 44, 45 and 46, or more as desired. The left hand segment 44 is pivoted at 47 to the vise 10. The right hand end of the right segment 46 is provided with a reduced tapered extension 48 loosely received in a correspondingly shaped strap 49 integrally secured to the vise 11.

The segments 44, 45 and 46 are shown pivotally connected at adjacent ends thereof, at pivot points 50 and 51, substantially forwardly of the adjacent rear edge portions of the segments, this inward spacing of the pivot points being a controlling factor with reference to the amount of stretching action applied to the part while being formed. The rearward faces of the segments 44, 45 and 46 are arcuately shaped as indicated at 44a 45a and 46a to provide, in the relative positions of the segments shown in Figure 3, a substantially

continuous predeterminedly arcuate forming surface portion corresponding to the desired shape of the article to be formed. According to circumstances or requirements, the pivots 50 and 51 may be located at varying distances from said forming portions of the segments, either forwardly or rearwardly thereof. The pivotal connection between the segments is accomplished by means of vertically extending rounded projections or ribs 52 and 53 at opposite ends of central segment 45, the same being received in correspondingly rounded vertical grooves or sockets 54 and 55 in ends of the outer segments. The adjacent ends of the segments are oppositely tapered from the pivot points 50 and 51, as indicated at 55, 56, 57 and 58, whereby the end portions of the segments at opposite forward and rearward sides of the pivots, may limit flexing movement forwardly substantially as shown in Figure 1, or rearwardly as shown in Figure 3. The flexing action of the die 43, during article-forming movement thereof to be described later, applies relatively strong pressure between the projections 52 and 53 and the reciprocal socket portions 54 and 55, but otherwise only relatively light means is required to hold the segments together. To this end, separation of the segments is prevented by provision of pins 60 on plates 61 secured at the ends of segments 44 and 46, these pins extending freely into recesses 62, 62 in the upper face of the central segment 45.

For flexing the die 43 rearwardly, from the inoperative position thereof shown in Figure 1 to the article-forming position thereof shown in Figure 3, a bifurcated link 63, pivoted to the central segment at 64, extends forwardly and is pivoted at its forward end to a pin 65 extending from a block 66 which is reciprocably slidable in spaced guides 71, 71 on support 12. Block 66 is a rearwardly and forwardly reciprocable, through a piston rod 78 extending forwardly from a fluid-pressure operated cylinder 79 suitably mounted at the rear of support 12.

The central segment 45 may be slidably supported on an arcuate guide strip 80, mounted on the top of support 12, and the segment 45 may have secured thereto a forwardly extending plate 82 from which depend spaced pins 83 and 84 which engage opposite sides of arcuate guide strip 80. This arrangement is such that engagement of the spaced pins 83 and 84 with the arcuate guide strip 80, during rearward flexing of the die 43 as urged under power of the cylinder 79, will effectively control the relative speed of angular movement of the segments about the pivot points 50 and 51, whereby the stretching action of the part P will be substantially uniform along the entire length thereof. Other suitable means may be utilized for controlling the relative angular velocities of the various die segments about the pivots 50 and 51.

When the straight unformed part P is in place for a forming operation, as shown in Figure 1, there may be some slack between the segments of the die 43. In order to take up this slack a releasable wedging device is provided at 85, by which initial compressive force is applied along the die, whereby upon rearward flexing of the same under pressure to engage the unformed part P the die will start stretching the part immediately.

This wedging mechanism 85 (see Figure 5 may comprise a wedge shaped block 86 which is insertable downwardly between the inner end face 11a of vise 11 and a tapered face 88 of a cut-out

portion 89 in the segment 46. For inserting and removing the wedge block 86 a link 90, pivoted at 91 to the top thereof, is pivotally connected at the other end at 92 to a handle 93 having a downward extension 94 pivoted to a bracket 95 secured to the top of the segment 46. By means of this arrangement the handle 93 is operable from the chain-dotted to the full line positions thereof illustrated in Figure 5, to force the wedge 86 into tight engagement between the vise and the segment to take up slack along the segments 44 to 46. Conversely the handle is operable in the opposite direction to remove the wedge after the part P has been formed, as shown in Figure 3, to facilitate reverse flexing of the die and to permit more ready removal of the part from the vise.

A desired degree of adjustment of the forming curvature of the die 43 may be obtained as by means of screws 97 and 98 threaded through lugs 99 and 100 on the forward sides of the two end segments 44 and 46, adjacent the inner ends thereof. These screws are adjustable as desired to be engageable with stop projections 101 and 102 at the correspondingly adjacent opposite ends of the intermediate segment 45, in the operative position of the die illustrated in Figure 3. Thus, through these screws, the forming curvature of the die may be altered to correct errors or accumulations of errors occurring in the production and assembly of dies, or to make alterations in the curvature as required by changes in design of parts, for example.

In the operation of the above-described apparatus for arcuately forming an aluminum extrusion, such as an angle bar for a reinforcing rib of an airplane, a straight length of extrusion material P is placed in the machine in the manner illustrated in Figure 1, by inserting opposite ends in the vises 10 and 11 and applying clamping action thereto by means of handles 38 thereof, substantially as described in connection with Figures 6 and 7. Next, the slack is taken up along the segments 44 to 46 of the die 43, by insertion of wedge 86 in the manner shown in full lines in Figure 5 and as fully described above.

Application of fluid pressure at the forward end of cylinder 79 will move the piston rod 78 rearwardly, and through link 63 attached to central segment 45, will flex the die 43 rearwardly against the unformed part P until the screws 97 and 98 engage the corresponding stops 101 and 102 on the central segment. With this rearward flexing, the opposite ends of the part P being restrainingly gripped by the vises 10 and 11, the outer die segments 44 and 46 will jamb tightly against the vises at opposing shoulder portions indicated at 10a and 11a, and at the same time jambing pressure will be applied at the die pivots or fulcrums 50 and 51. In the last described condition the die 43 will be fully flexed, as shown in Figure 3, and the part P stretch-formed to finished arcuate shape.

To facilitate removal of the finished part from the vises 10 and 11 first the wedging device, best illustrated in Figure 5, is operated through handle 93 to remove wedge 86 (see chain-dotted lines), thereby to relieve the residual strain along the die segments, after which the handles 38 of vises 10 and 11 are operable to release the clamping blocks 21 and 22. Lateral movement of vise 11 relatively of segment 46, as permitted by the loose engagement of fixed roller 16 in guard 15, greatly facilitates insertion and re-

moval of the ends of the part P with respect to both vises.

If upon checking the finished part the curvature thereof is found not to be substantially exact, the screws 97 and 98 may be adjusted for succeeding operations of the machine until the parts are formed accurately.

Although the apparatus has been described for use in stretch-forming relatively narrow bar stock, it will be readily understood that the apparatus with slight modifications may be utilized for similarly stretch-forming sheet material or other material of substantial widths. It will be understood also that any number of die segments may be utilized in accordance with particular requirements pertaining, for example, to the lengths or shapes of the parts.

Referring to Figure 8 of the drawings, there is illustrated a modified form of the invention particularly adapted for forming parts to have an S-bend or other compound curvature. In this form of the invention the stretch-forming die is in two parts indicated at 105 and 106, arranged to be at opposite sides of a straight piece of extrusion angle of other material to be formed. Each die part 105 and 106 may comprise a pair of transversely and laterally oppositely arranged die segments 107, 108, 109 and 110, the central or inwardly adjacent segments 107 and 109 being suitably fixedly mounted on a flat supporting member or table 111. The outer segments 108 and 110 are pivotally connected at 113 and 114 to the fixed inner segments 107 and 109, respectively, substantially in the same manner as previously described in connection with Figures 1 to 7. Suitably secured to the outer segments 108 and 110 may be oppositely disposed vises 115 and 116 substantially like the vises 10 and 11 described above, for similarly clamping opposite ends of a straight length of angle bar P₁ or other sectional material, as shown in full lines. The vises 115 and 116 have pivoted thereto, at 117 and 118, links 119 and 120 the other ends of which are pivoted at 121 and 122 to opposite end of a bar 123 which is pivoted at 124 intermediate said ends to the top of fixed segment 107.

This arrangement is such that a link 125 pivotally connected to the bar 123 at 121, is adapted to be urged rearwardly, as by suitable power means (not shown), and through the links 119 and 120 to move vises 115 and 116 in opposite rearward and forward directions, respectively, to the chain-dotted line position of Figure 8. This compound rearward and forward flexing of the die parts 105 and 106, respectively, as urged by corresponding bending of the opposite ends of the part P₁ is effective to form the part to S-shape corresponding to the curved forming portions of the die segments. In other words, the stretch-forming action of this form of the invention is substantially equivalent to two oppositely arranged flexible dies of the type previously described in connection with Figures 1 to 7.

The fully formed part P₁, illustrated in chain-dotted lines in Figure 8, is readily removable by releasing clamping mechanism of vises 115 and 116 in the manner described above for the first-mentioned form of the invention.

Other modifications of the invention may be resorted to without departing from the spirit thereof or the scope of the claims.

What is claimed is:

1. Apparatus for stretch-forming metal parts, comprising a support, a pair of vises for releasably gripping opposed ends of a part to be formed,

means for relatively shiftably mounting said vises on said support to be maintained in predeterminedly spaced apart relation restrainingly to hold the unformed part while gripped at said opposed ends thereof, an elongate segmental die connected at opposite ends to said shiftable vises and providing part-forming surface portions along the die to be engageable along the length of the unformed part, the segments of said die being pivotally joined at adjacent ends, the pivot points of adjacent segments being spaced substantially inwardly of said part-forming portions of the die in the direction which would be away from the part, means for positively limiting flexing of said die to provide a predetermined contour along said part-forming portions and power means for flexing said die to said predetermined contour against the part while restrained between said vises.

2. Apparatus for stretch-forming metal parts, comprising a support, a pair of vises for releasably gripping opposed ends of a part to be formed, means for mounting said vises on said support to be relatively shiftable in opposite arcuate directions while maintained in predeterminedly spaced apart relation with respect to a point intermediate said vises restrainingly to hold the unformed part while gripped at said opposed ends thereof, an elongate segmental die connected at opposite ends to said shiftable vises and providing part-forming surface portions along the die to be engageable along the length of the part, the segments of said die being pivotally joined at adjacent ends, the pivot points of adjacent segments being spaced substantially inwardly of said part-forming portions of the die in the direction which would be away from the part, adjustable means for positively limiting flexing of said die to provide a predetermined contour along said part-forming portions, and power means for flexing said die to said predetermined contour against the part while restrained between said vises and thereby to stretch-form said unformed part to acquire said predetermined contour.

3. Apparatus for stretch-forming metal parts, comprising a support, a pair of vises for releasably gripping opposed ends of a part to be formed, means for relatively shiftably mounting said vises on said support to be maintained in predeterminedly spaced apart relation restrainingly to hold the unformed part while gripped at said opposed ends thereof, an elongate segmental die connected at opposite ends to said shiftable vises and providing part-forming surface portions along the die to be engageable along the length of the unformed part, the segments of said die being pivotally joined, adjustable means for positively limiting flexing of said die to provide a predetermined contour along said part-forming portions, and power means for flexing said die to said predetermined contour against the part while restrained between said vises and thereby to stretch-form said unformed part to acquire said predetermined contour.

4. Apparatus for stretch-forming metal parts, comprising a support, a pair of vises for releasably gripping opposed ends of a part to be formed, means for relatively shiftably mounting said vises

on said support to be maintained in predeterminedly spaced apart relation restrainingly to hold the unformed part while gripped at said opposed ends thereof, an elongate segmental die connected at opposite ends to said shiftable vises and providing part-forming surface portions along the die to be engageable along the length of the unformed part, adjacent ends of the segments of said die being pivotally joined with the pivot points being spaced substantially inwardly of said part-forming portions of the die in the direction which would be away from the part, adjustable means for positively limiting flexing of said die to provide a predetermined contour along said part-forming portions, and power means for flexing said die to said predetermined contour against the part while the same is restrained between said vises and thereby to stretch-form said unformed part to acquire said predetermined contour.

5. Apparatus for stretch-forming metal parts, comprising a support, a pair of vises for releasably gripping a part to be formed, means for mounting said vises on said support restrainingly to hold the unformed part while gripped at spaced points by the vises, an elongate segmental die connected at opposite ends to said vises and providing part-forming surface portions along the die to be engageable along the length of the part, adjacent ends of the segments of said die being pivotally joined with pivot points thereof being spaced substantially inwardly of said part-forming portions of the die in the direction which would be away from the part means at said adjacent ends of said segments for limiting article-forming flexing of the die to provide a predetermined contour along said part-forming portions, power means for flexing said die to said predetermined contour against the part while the same is restrained between said vises, guide means on said support for controlling the direction of said flexure of said die, and releasable take-up means for adjusting the slack between said die segments.
